PROCESS FOR MAKING ELECTRIC
CONDENSERS

Felix Weiss, Plainfield, N. J., assignor to Cornell-Dubilier Electric Corporation, South Plainfield, N. J., a corporation of Delaware

Application January 22, 1938, Serial No. 186,339

8 Claims. (CL. 164—18)

The present invention relates to an improved method of and apparatus for punching a plurality of pieces of desired angular configuration from coherent sheet material. More specifically, although not limited thereto, the invention is concerned with cutting a plurality of square or rectangular pieces of equal or different size out of a sheet of insulating material such as mica or the like for use as dielectric elements in the construction of electrical condensers.

Single pieces of dielectric sheet material of desired equal or different shapes had to be punched heretofore from mica sheets or the like in such a way as to leave unused portions between the individual pieces. This method of cutting involved a substantial loss in material and furthermore, due to the brittle or laminated structure of the material, particularly mica, the corners were often splintered or broken so that many of the punched pieces had to be rejected and could not be used. Furthermore, in the case of laminated material such as mica, the laminae of the material became partially separated along the edges of the punched pieces due to the shearing and other stresses exerted thereon during the cutting operation.

Accordingly, it is an object of the invention to increase the efficiency of cutting or punching sheet material into pieces or units of any desired shape especially from laminated brittle or easily splintered sheets such as mica or similar material.

Another object is to cut or punch such pieces of angular shape from the stock material, especially laminated brittle or easily splintering material such as mica, without waste of material between the punched pieces.

Another object is to obtain in an efficient and easy manner exact shapes with unbroken and unsplintered edges or corners.

These and further objects of the invention will become more apparent from the following detailed description taken with reference to the accompanying drawing forming part of this specification and wherein

Figure 1 illustrates the manner of cutting a number of rectangular pieces from a sheet of mica or the like in accordance with previous known methods, Figure 2 illustrates the cutting of such pieces in accordance with the improved method proposed by the invention, Figure 3 is an isometric view of a suitable combination punching and cutting die for practicing the invention with the upper die half removed, Figure 4 is a cross-section through the complete cutting die taken on line 4—4 of Figure 3, and Figure 5

is a further cross-section of the complete cutting die taken on line 5—5 of Figure 3.

Similar reference numerals designate similar parts throughout the different views of the drawing.

Although many modifications and uses of the invention will be apparent, for clearness of the specification the invention will be described particularly by way of example as applied to the cutting or punching of mica sheet material, but it will be evident from the following that many modifications and variations may be resorted to differing from the specific steps and combination of elements described herein for purposes of illustration.

Referring more particularly to Figure 1 of the drawing illustrating the method of cutting rectangular pieces from a sheet as practiced in the prior art, the pieces 10 are cut or punched from the sheet 11 of mica or the like leaving the spaces 12 or portions 12 therebetween which are unusable or wasted. In the example shown it is assumed that the pieces 10 are cut in a regular pattern by a multiple die of suitable construction. If the pieces are cut by hand in a more or less haphazard manner; that is, one at a time, the waste due to unusable material between the cut elements may be still greater as is readily understood.

If in Figure 1 the pieces 10 were cut closely adjacent to each other or in other words, if the spaces 12 were reduced by the use of a suitable multiple cutting die, the corners 13 of the cut-out pieces would in many cases become torn or splintered and useless for many practical applications especially as dielectric elements or plates in an electrical condenser. Furthermore, in the case of laminated material such as mica, the laminae may become partly separated along the edges such as indicated by the dotted line at 14 in Figure 1 due to the non-resiliency of the mica and to the bending and shearing stresses exerted upon the edges during the cutting operation.

According to the improved method proposed by the present invention and illustrated in Figure 2, the sheet 11 of mica or the like is first punched with small holes 15 by means of multiple pins in a suitable punching die. The punching pins and cooperating holes in the punching die are arranged in such a manner that the holes will be punched in the mica sheet at the corners of the desired square or rectangular pieces to be cut out. Subsequently, the sheet is cut along straight lines 16 interconnecting the holes 15 thereby obtaining punched pieces of the desired

size and configuration; that is, rectangular pieces in the example illustrated without the defects and difficulties encountered in the previously known methods and substantially without loss 5 or waste of material.

Due to the small size of the holes 15 and the fact that the stresses on the edges and corners during the cutting operation are greatly reduced or eliminated, a tearing or splintering of the 10 cut-out pieces especially at the most endangered corners is substantially avoided. Rectangular elements obtained in this manner have their corners slightly rounded inwardly or trimmed along an arcuate line or curve. The size of this curve 15 is determined by the size of the holes and in most cases should be as small as possible. In the case of punching mica sheets for use in electric condensers a diameter of the corner holes of about .04" has been found to give satisfactory 20 results.

Furthermore, the elimination of sharp perpendicular corners substantially prevents tearing of the corners of the cut out pieces, and furthermore results in a decrease of the friction between 25 the elements and the walls of the punching die and in turn in increased resiliency of the edges of the elements thereby preventing to a marked degree a separation of the lamina of the sheets along the cut edges as experienced with previous 30 cutting methods pointed out hereinabove.

As will be apparent from the above, by employing the principle and method of the invention, elements of rectangular or any other shape may be cut from a sheet with the edges of the 35 elements closely adjacent to or coinciding with each other, thereby entirely eliminating the waste material due to the separating spaces required in past cutting operations. In this manner by the new method an approximate saving of about 40 30% of material is obtained.

The perforating and subsequent cutting of the sheets according to the invention may be carried out by means of any suitable punching and cutting die. A preferred and improved device of 45 this type is shown in Figures 3 to 5. The latter constitutes a combination of perforating and cutting or shearing units with means for ensuring the proper relative position of the sheet to be punched during the perforating and cutting operations, 50 respectively, to ensure the cutting of the sheet along connecting lines between the previously punched holes in a manner described hereinabove.

Referring to the drawing, Figures 3 to 5, there 55 is shown a cutting device having lower and upper base members or supporting plates 20 and 21. The lower supporting plate 20 has a punching die plate or section 22 and an adjacent cutting or shearing section 23 fixed thereto. Similarly, the 60 upper supporting plate 21 carries punching and cutting die plates 24 and 25, respectively, the former being arranged to cooperate with the lower punching die plate 22 and the latter being arranged to cooperate with the lower cutting or shearing die section 23. Numeral 26 represents 65 a guide post or the like for properly guiding the upper half or plate 21 of the die during the punching and cutting operations. The bottom die plate 22 of the hole punching unit is provided 70 with holes 27 registering with pins 28 secured to or integral with the upper die plate 24. There is further shown a stripping plate 29 having perforations allowing free passage of the pins 28 and resiliently mounted upon the plate 24 by 75 means of pins or studs 30 arranged to pass freely

through corresponding perforations in the plate 24. The pins 30 are formed with enlarged heads arranged to move in correspondingly enlarged portions 31 of the perforations in the plate 24. Resilient spacing members 30' such as strips of 5 rubber or equivalent material are placed between the plates 24 and 29 and secured thereto such as by screws or rivets or in any other suitable manner.

The operation of the hole punching unit described is readily understood. When the upper die plate is moved downward by hand or by the aid of a power driven device, the pins 28 will push through the mica sheet 32 and engage the holes 27 of the lower die plate thereby punching 10 out round holes from the sheet 32 in the manner as shown in Figure 2. When the upper die plate is again moved upwardly the stripping plate 29 having previously been pressed towards the plate 24 by compression of the spacing members 15 20 30' is pushed again downwardly due to the resiliency of the members 30', thus stripping off the mica piece 32 and preventing its sticking to or being torn or bent by the upward movement of the plate 24. 25

After the sheet 32 has been punched with holes in the manner described and arranged for instance such as shown in Figure 2, it is moved to the shearing unit for cutting along the lines interconnecting the holes punched therein as 30 previously described. The cutting or shearing unit in the example illustrated comprises a lower part consisting of alternate stationary and movable rectangular elements or shearing blocks 35 and 36 respectively. The former are rigidly fixed 35 to or integral with the base plate 20 and the latter are arranged in snugly fitting but sliding relation between the fixed blocks for up and down movement against the action of resilient elements such as metal springs or rubber cushions 37 arranged 40 between the lower faces of the blocks 36 and the base plate 20. The top part of the cutting die unit is the same as the bottom part described and comprises alternate stationary shearing blocks 38 fixed to the top supporting plate 45 21 and movable shearing blocks 39 held by pins or studs 41 fixed to the plate 21 and passing through perforations in the blocks 39. The latter 50 perforations terminate in enlarged portions 42 adapted to receive the heads of the pins 41 thereby holding the blocks 39 in position and permitting the same to move towards the supporting plate 21 against the action of resilient 55 cushions 40 similar as in the case of the blocks 36 of the lower part of the die. The top part 55 25 of the cutting die is furthermore arranged with its stationary shearing blocks 38 registering with the movable shearing blocks 39 of the bottom 60 part or section 23 and vice versa with the stationary blocks 35 of the bottom section registering with the movable blocks 39 of the top section, in such a manner that when the die is closed, the stationary blocks 38 of the top part will force the movable blocks 36 of the bottom part 65 downward in a direction against the bottom plate 20 and against the action of the rubber cushions 37 and alternately, the stationary shearing blocks 35 of the lower die part will force the movable blocks 39 of the upper part upwardly 70 toward the top supporting plate 21 and against the action of resilient cushions 40. Thus, when the die is closed and sufficient pressure applied, the movable shearing blocks recede in an upward or downward direction, respectively, thereby effecting the shearing or cutting of the mica or other 75

sheet 32 along the edges of the blocks 35, 36, 38, 39 and subdividing it into corresponding rectangular elements in the manner described. As pointed out, the mica sheet 32 or the like must be positioned and held in the cutting die in such a manner that the shearing edges of the die are in alignment with the holes 21 which have been previously punched in the sheet.

The positioning of the sheet 32 in the punching die and corresponding positioning in the cutting die may be carried out in a number of manners such as by a suitable guide arrangement described hereafter, or by punching a number of positioning holes in the sheet fitting over corresponding marking or positioning pins located in the cutting die unit.

In the example illustrated in Figure 3, the positioning of the sheet in the respective dies is obtained in a more or less automatic manner. The sheet 32 is first placed on a loading platform 46 with a portion extending beyond the platform as shown. A sliding clip having upper and lower elements or tongues 47 and 48 is fixed to a sliding member or block 50 moving upon a guide rail 51 secured to a lateral extension of the bottom plate or support 20 in such a manner that it may be moved from a position opposite to the loading platform to a position opposite to the punching die unit and from there to a corresponding position opposite to the cutting die unit. Stops 52, 53 and 54 secured to the rail 51 serve to fix the positions of the block 50 or clip relative to the loading punching and cutting die units, respectively. A trip roller 55 having a stop hinge section 56 allowing to drop the roller in a backward position is secured to the base plate 20 in such a position that as the block 50 is moved to the position in front of the loading platform 46, the lower tongue 48 of the clip passes over the roller 55 until its downwardly bent rearward extension 49 engages the roller at which time the clip jaws 56 and 57 open as the block 50 is moved further forward toward the stop position. The clip jaws 57 and 57' thus slip over the extending portion of the sheet 32 and as the clip or block 50 is moved further in the same direction, the clip will spring into closing position thus firmly gripping the extension of the sheet 32. The support for the roller 50 may be held in a vertical position by a coil spring having one end attached thereto and having its other end secured to the base plate in such a manner that as the block 50 is moved to the punching position, the end of the clip will trip the roller backwards and pass over the same without opening the clip jaws. The latter may be provided with teeth or prongs to ensure a firm gripping of the mica sheet or the like thereby maintaining accurate relative position of the sheet to be punched in the hole cutting and shearing die units respectively.

After the holes 21 have been punched in the manner described, the sheet 32 is moved to the cutting position by releasing the stop element 53 and moving the block 50 towards the right until abutting against the stop element 54.

While there has been shown a particular combination of elements to illustrate one way of carrying out the invention, it is to be clearly understood that any one of the elements can be used by itself or with any other element besides those shown and illustrated, without departing from the scope of the invention.

Moreover, as will be evident from the above, the invention is not limited to the specific ap-

paratus and combination of elements and methods disclosed for illustration, but is susceptible of numerous variations and modifications coming within its broader scope and spirit as defined in the appended claims.

The specification and drawing are accordingly to be regarded in an illustrative rather than a limiting sense.

I claim:

1. In a device of the character described, a punching die unit for punching a plurality of small holes in a sheet at the corners of a plurality of elements into which said sheet is to be sub-divided, a cutting die unit for cutting said sheet along lines connecting the holes punched therein, a movable support for said sheet, a guide for said support, and stop means for said support to position said sheet in the proper relative positions in said punching and cutting units.

2. In a device as claimed in claim 1 wherein said punching die unit comprises a pair of cooperating portions, one of which is provided with a plurality of punching pins engaging corresponding holes in the other portion, and wherein said cutting unit comprises a plurality of adjacent shearing elements, and a pair of common supporting members for the corresponding portions of said dies.

3. In a device of the character described, a punching die unit for punching a plurality of small holes in a sheet at the corners of a plurality of elements into which said sheet is to be sub-divided, a cutting die unit for cutting said sheet along lines connecting the holes punched therein, said punching die unit comprising cooperating lower and upper portions, one of said portions being provided with a plurality of punching pins engaging corresponding holes in the other portion, said cutting die unit also comprising upper and lower portions with a plurality of cooperating adjacent shearing elements, a pair of common supporting members for the respective upper and lower portions of said dies, a carrier member slidably mounted and adapted to rigidly hold the sheet to be cut, and stop means for said carrier member for fixing the relative positions of said sheet in said punching and said cutting dies, respectively to cut said sheet along lines connecting holes punched therein.

4. In a device of the character described, means for punching a plurality of small holes in parallel rows in a sheet, said holes defining the corners of a plurality of elements into which said sheet is to be sub-divided, further means for cutting said sheet along the lines connecting said holes, said last means comprising a pair of cooperating units, each unit comprising alternately fixed and movable shearing members conforming to the shape of the elements to be cut, the fixed shearing members of one unit registering with the movable shearing members of the other unit and vice versa, and means for positioning a sheet to be cut with respect to said first and second means, respectively, so that the holes punched by said first means register with the respective meeting corners of the shearing members of said second means.

5. In a device of the character described, means for punching a plurality of small holes in mutually perpendicular rows in a sheet, said holes defining the corners of a plurality of rectangular elements into which said sheet is to be subdivided, further punching means for cutting said sheet along the lines connecting said holes, said last punching means comprising a pair of co-

operating units, each unit comprising alternately fixed and movable shearing members conforming to the shape of the elements to be cut, the fixed shearing members of one unit registering with the movable shearing members of the other unit and vice versa, and means for positioning a sheet to be cut with respect to said first and second means so that the holes punched by said first means register with the respective meeting corners of the shearing members of said last punching means.

6. In a device of the character described, means for punching a plurality of small holes in mutually perpendicular rows in a sheet, said holes defining the corners of a plurality of rectangular elements into which said sheet is to be subdivided, further punching means for cutting said sheet along the lines connecting said holes, said last means comprising a pair of cooperating units, each comprising alternately fixed and movable shearing members conforming to the shape of the elements to be cut, the fixed shearing members of one unit registering with the moving shearing members of the other unit and vice versa, resilient supporting means for said movable shearing members of each unit, whereby said movable shearing members of each unit are normally flush with the fixed shearing members of the same unit and adapted to recede when engaged by the cooperating fixed shearing members of the other unit during the closing of said further punching means, and means for positioning a sheet to be cut in said first and second punching means, respectively, so that the holes punched by said first means register with the respective meeting corners of the shearing members of said second means.

7. In a device of the character described, means for punching a plurality of small holes in mutually perpendicular rows in a sheet, said holes defining the corners of a plurality of rectangular elements into which said sheet is to be subdivided, further punching means for cutting said sheet along the lines connecting said holes, said last punching means comprising a pair of cooperating

units, each of said units comprising alternately fixed and movable shearing members conforming to the shape of the elements to be cut, the fixed shearing members of one unit registering with the movable shearing members of the other unit and vice versa, a carrier member slidably mounted and adapted to rigidly hold a sheet to be cut, and stop means for said carrier member for fixing the relative positions of said sheet in respect to said first and second punching means so that the holes punched by said first means register with the respective meeting corners of the shearing members of said second punching means.

8. In a device of the character described, means for punching a plurality of small holes in mutually perpendicular rows in a sheet, said holes defining the corners of a plurality of rectangular elements into which said sheet is to be subdivided, further punching means for cutting said sheet along the lines connecting said holes, said last means comprising a pair of cooperating units, each of said units comprising alternately fixed and movable shearing members conforming to the shape of the elements to be cut, the fixed shearing members of each unit registering with the movable shearing members of the other unit and vice versa, resilient supporting means for said movable shearing members in each unit, whereby the movable shearing members of each unit are normally flush with the fixed shearing members of the same unit and adapted to recede when engaged by the cooperating fixed members of the other unit during closing of said last punching means, a carrier member slideably mounted and adapted to rigidly hold a sheet to be cut, and stop means for said carrier member for fixing the relative positions of said sheet in respect to said first and second punching means, whereby the holes punched by said first punching means register with the respective meeting corners of the shearing members of said second punching means.

FELIX WEISS. 45
